UNITED STATES PATENT OFFICE.

LOUIS E. WHITTINGTON AND WEED ROBINSON, OF SILVIS, ILLINOIS.

SUPERHEATER.

Application filed June 20, 1921. Serial No. 479,167.

This invention relates to a superheater for locomotive engines and particularly to improvements in the header construction for the same. One object is to provide an arrangement whereby only superheated steam is throttled. Another object is to provide a construction wherein the superheater elements are always filled with steam. Another object is to obviate the need of a damper. 10 Other objects will appear from time to time throughout the specification and claims.

The invention is illustrated more or less diagrammatically in the accompanying drawings, wherein—

15 Figure 1 is a vertical cross section through a locomotive boiler taken just in front of the header;

Fig. 2 is a vertical longitudinal section on an enlarged scale taken on line 2—2 of 20 Fig. 1;

Fig. 3 is a section on an enlarged scale taken on line 3—3 of Fig. 2;

Fig. 4 is a horizontal section taken on line 4—4 of Fig. 3;

25 Fig. 5 is a sectional detail of the valve taken on line 5—5 of Fig. 2;

Fig. 6 is a detail sectional view of the valve taken on line 5—6 of Fig. 2;

Fig. 7 is a horizontal section of the valve 30 taken on line 7—7 of Fig. 5;

Fig. 8 is a horizontal section of the valve on line 8—8 of Fig. 6;

Fig. 9 is a plan view of the header;

Fig. 10 is a diagrammatic showing of the 35 superheater elements;

Fig. 11 is a section on an enlarged scale taken on line 11—11 of Fig. 10;

Fig. 12 is a section on an enlarged scale taken on line 12—12 of Fig. 2;

40 Figure 13 is a section on line 13—13 of Fig. 3.

Like parts are designated by like characters throughout.

A is the shell of a locomotive boiler. B is 45 an end plate of the boiler. B' B' are small flues extending through the boiler and terminating at the plate B through which they pass. B² B² are a plurality of large flues within which the super-heater elements are 50 positioned.

D is the header provided with the water inlets D' D' which communicate with any suitable source of water supply not here illustrated in detail. D² D² are outlets from

the header to the boiler. Water in passing 55 through the header is heated before it passes to the boiler. D³ D³ are steam outlets from the header to the engine cylinders, not here shown in detail as they form no part of the present invention. D⁴ is a valve dome on 60 the top of the header within which is located the throttling valve, which is carried on the vertical shaft D⁵ upon which is mounted the rack D⁶. D⁷ is a pinion carried on a shaft D⁸ which is supported at bearings D⁹ 65 D⁹ and adapted to be rotated by means of the link D¹⁰, the details of which are not here shown as they form no part of the present invention. D¹¹ is an outlet pipe for superheated steam which passes back along the 70 locomotive to any suitable connection where it may be applied to run a compressor, operate a turbine generator, used for heating the train, or any other desired purposes.

The construction of the header itself will 75 now be described. The header proper is divided into an upper and lower level. Saturated steam from the boiler enters the upper level through the intake pipe E, which is open at its top, into the steam dome E'. 80 This pipe communicates with the upper channel E² which extends across the top of the header. Saturated steam entering this channel goes down into the wells E³ E³ of which there are 6, although this number 85 could of course be considerably varied. The wells E³ as shown in Fig. 4 are open from above throughout approximately one-third of their length. When the steam has entered these wells, it entirely fills them and passes 90 down through the perforations E⁴ E⁴ in all of the wells, through which perforations the superheater elements C are connected. Through these elements it circulates back 95 and forth in the flue and finally after being superheated, it comes into the wells E⁵ which are spaced between the wells E³. From these wells it rises through the openings in the center through the upper walls into the longitudinal channel E⁶ which is provided 100 at its center with the enlarged chamber E⁷ within which is located the throttling valve.

Feed water enters the header by means of the pipes D' D' which communicate with the longitudinal channel F across the front 105 of the header, thence through the perforations F' F' between the steam wells E³ E⁵ water passes into the longitudinal channel

F² which extends across the rear of the header. From this channel it passes through the pipes D² D² into the boiler. Thus the water is heated by means of the steam before it enters the boiler.

We shall now describe the course of the steam through the superheater elements proper. This is shown in detail in Figs. 10 and 11. Saturated steam coming from the 10 header enters the superheater element through the pipe C' moving in the direction of the arrow. It moves thence along the pipe to its end and through the connection C² to the pipe C³ and thence back to the end 15 of that pipe to the connection C⁴ and into the pipe C⁵ to the end of that pipe to the connection C⁶, and into the pipe C⁷, and thence back to the connection C⁸ and into the pipe C⁹ and forward through that pipe 20 to the connection C¹⁰ and into the pipe C¹¹, and upward through the bend C¹² which is a continuation of the pipe C¹¹ and so into the superheated steam well of the header. Thus the saturated steam passes six times the 25 length of the boiler flue, being superheated in the process and finally returns to the header.

The detail of the connection of the superheater units to the floor of the header will 30 now be described as particularly illustrated in Fig. 12. The pipe C' leads from the floor of the saturated steam well E³ and the pipe C¹² returns to the floor of the superheated steam well E⁵. Each of the pipes terminates 35 in the nipple C¹³ which fits into an opening in the bottom of the steam well. Embracing each of the pipes and bearing upon the washers C¹⁴ is the yoke C¹⁵ which is secured to the floor of the header by means of the 40 bolt C¹⁶ and nut C¹⁷. The tightening of this nut and bolt draws the yoke against the bottom of the header and thus fastens and holds the superheater pipes in position.

The construction and operation of the 45 valve will now be described. The valve elements are located within the dome D⁴ and are mounted upon the shaft D⁵. As shown in all the figures the valve is closed. Superheated steam enters the valve through a number 50 of ports, two of them G G located immediately beneath the valve, and two other ports G' G' about the upper part of the valve and leading from the chamber E⁶. Outlet ports G⁵ are located towards the middle 55 of the valve and in front of its axis. When the valve is raised so that the passage between the inlet and outlet ports is no longer blocked by the valve discs G⁴, G⁴ superheated steam enters the valve through the 60 lower and upper inlet ports G, G' respectively towards the rear of the valve and passes thence through the center of the valve and out through the outlet ports G⁵ G⁵ toward the middle and front of the valve, into 65 a third longitudinal channel or chamber E⁷

and thence through the pipes D⁸ D⁹ to the engine cylinders.

The throttle mechanism for operating the throttle valve is adapted for use with a variety of different types of locomotives. In some cases it is necessary to locate this mechanism lower than as shown. For this purpose the two domes H are provided. They may be located opposite each other at any point in the circumference of the boiler. The bearings D¹⁰ D¹⁰ for the shaft D⁸ are secured to the semispherical surfaces of the domes H. Where the domes are located lower on the boiler than as shown the bearings would be located higher on the dome and a great variety of adjustment is thus made possible.

The idea is that the domes H may be positioned upon the boiler surfaces according to the way the designer desires and the bearings for the throttle shaft may be located on the face of the dome dependent upon the position of the dome on the boiler because its angular position will vary with its movement about the boiler circle.

Since steam is throttled only as superheated steam and after it has passed through the boiler, the superheater elements, and the superheater header, all of the elements of the superheater assembly are under substantially constant boiler pressure and thus there is practically no expansion or contraction of these elements and their life is thus rendered considerably longer as wear upon them is greatly reduced. As the superheater elements are constantly full of steam at constant pressure, it is not necessary, as is usually the case, to provide a closure for the boiler flues, and thus no damper is necessary in connection with this invention.

Although we have shown an operative device, still it will be obvious that many changes might be made both in size, shape and arrangement of parts without departing materially from the spirit of our invention, and we wish therefore that our drawings be regarded as in a sense diagrammatic.

The use and operation of our invention are as follows:

Water comes into the channel along the front of the header and passes thence between the steam wells into the channel along the back of the header and so comes into the boiler. Since there is steam in the steam wells and since the header is thus heated, the water in passing through it becomes heated and so comes into the boiler in a heated condition. The saturated steam from the boiler comes up into the dome and is drawn thence into the header and passes through the saturated steam wells in the header into the superheater elements and through them and back into the header through the superheated wells and into the chamber on the top of the header. When the

valve is open the superheated steam of course passes through it and out to the engine cylinders.

We claim:

5. 1. The combination with a boiler of a superheater assembly including superheater elements and a header, said header in communication with said boiler, saturated steam chambers within said header and super-
10 heated steam chambers within said header, a plurality of feed water chambers within said header and a valve chamber within said header, said superheater elements connected each at one end to a saturated steam chamber and at the other end to a superheated steam chamber, said valve chamber in communication with said superheated steam chambers and so constructed as constantly to be surrounded by superheated steam, said 15 plurality of feed water chambers lying in part between said steam chambers. 65
2. The combination with a boiler of a header adapted for use in connection with superheater assemblies comprising a plurality of alternating saturated steam and superheated steam chambers and having a passage in communication with said superheated steam chamber, a plurality of feed water passages located intermediate said 20 saturated and superheated steam chambers and a throttling valve in part within said passage, all the parts comprising the throttling valve assembly and especially including the movable valve elements, the housing walls and the valve seats being entirely surrounded at all times by superheated steam and being entirely located within the confines and removed from the walls of the locomotive smoke box. 25
3. The combination with a boiler of a header adapted for use in connection with superheater assemblies comprising a plurality of alternating saturated steam and superheated steam chambers and having a passage in communication with said superheated steam chamber and a throttling valve in part within said passage, and a feed water heater within said header, comprising a plurality of laterally extending passages positioned between said saturated and superheated steam chambers. 30
4. The combination with a boiler of a header adapted for use in connection with superheater assemblies comprising a plurality of alternating saturated steam and superheated steam chambers and having a passage in communication with said superheated steam chamber, a plurality of feed water passages located intermediate said saturated and superheated steam chambers and a throttling valve in part within said passage, and a feed water heater within said header, comprising a plurality of laterally extending passages positioned between said saturated and superheated steam chambers. 35
5. A locomotive superheater and feed water heater, comprising a header having saturated steam chambers and superheated steam chambers and passages for feed water located between the said chambers, whereby the opposite walls of the water passages are exposed to direct action of both the saturated steam and the superheated steam, and superheater elements connected with and intermediate of the saturated steam chambers and the superheated steam chambers of the header. 40
6. A locomotive superheater and feed water heater, comprising in combination a body portion, a horizontal partition member in said body portion, dividing it into upper and lower sections, and vertical partitions forming a plurality of alternately positioned saturated and superheated steam chambers in said body on one of said sections, and a plurality of feed water passages extending laterally between said chambers for exposing the feed water to the direct action of the superheated steam. 45
7. A combined locomotive superheater and feed water heater, comprising a body portion, a partition located in said body portion, dividing it into upper and lower sections, a plurality of saturated and superheated steam chambers located within said body on one of said levels, each chamber being separated from an adjacent chamber by a wall member, and a plurality of passages extending through said wall members for conducting feed water therethru, the said 50 passages terminating in passages extending longitudinally of the heater body. 55
